DESIGN FOR A COMBINATION TWIN BED UNIT

Truman S. Ziegenfuss, Los Angeles, Calif.

Application April 28, 1947, Serial No. 138,660

Term of patent 14 years

(Cl. D5—4)

To all whom it may concern:

Be it known that I, Truman S. Ziegenfuss, a citizen of the United States, residing at Los Angeles, in the county of Los Angeles and State of California, have invented a new, original, and ornamental Design for a Combination Twin Bed Unit, of which the following is a specification, reference being had to the accompanying drawings, wherein:

Figure 1 is a perspective view of a twin bed unit, showing my new design, the beds being shown in a separated position; and

Figure 2 is a perspective view of the unit of Figure 1, but with the beds shown in abutting position.

I claim:

The ornamental design for a combination twin bed unit, as shown.

TRUMAN S. ZIEGENFUSS.
